United States Patent Office

Des. 183,775
Patented Oct. 21, 1958

183,775

COMBINED TARGET AND BALL RETURN APPARATUS OR SIMILAR ARTICLE

Henry C. Sylvester, Los Angeles, and Zackary Woods,
Hollywood, Calif.

Application September 23, 1957, Serial No. 47,806

Term of patent 14 years

(Cl. D34—5)

Fig. 1

Fig. 2

Fig. 3

Figure 1 is a perspective view of a combined target and ball return apparatus or similar article, showing our new design;

We claim:

The ornamental design for a combined target and ball return apparatus or similar article, substantially as shown.
